CHAIN GUARD

Application filed June 8, 1923. Serial No. 644,181.

The present invention relates to certain new and useful improvements in chain guards, adapted to protect the cutter chain of a coal mining machine from accidental contact with the person of the operator.

A shortwall mining machine, as commonly constructed, comprises a main frame and an elongated horizontally projecting kerf cutter rigidly attached thereto. When such a machine is handled in the dark and restricted chambers of a coal mine, the operator and his helper are in constant danger of accidental contact with the unprotected moving cutter bits, and to avoid this danger a shield has been provided which is adapted to lie outside of and above the path of the moving cutter bits to protect the operator and his helper therefrom. As the kerf cutter is thrust longitudinally into the coal the forward end of this shield contacts with the coal face and is pushed rearwardly into a recess of the main frame. As heretofore constructed this shield must be manually restored to guarding position when the kerf cutter is withdrawn from the coal, and, since the kerf cutter is usually approximately twice the length of the main frame, such shields have left the forward part of the kerf cutter unprotected.

It is the especial object of this invention to provide a chain guard adapted to extend along the entire length of the kerf cutter of a shortwall mining machine when said cutter arm is outside of the kerf, and which may be collapsed into the frame of the machine as the kerf cutter is thrust longitudinally into the coal.

A further object is to provide a chain guard of the class described which will automatically return to its extended position along the kerf cutter as said kerf cutter is withdrawn from the kerf.

These and other objects will be fully set forth in the following specification reference being had to the accompanying drawings of which—

Fig. 1, is a plan view of a shortwall mining machine equipped with the devices of my invention.

Fig. 2, is a side elevation of the machine illustrated in Fig. 1.

Fig. 3, is a section taken along the line III—III of Fig. 1.

Figure 4 is a transverse section taken on the line 4—4 of Figure 1.

Figure 5 is an enlarged elevation illustrating the relation of the telescoping sections of the guard at one side of the machine.

Like numerals refer to similar parts in the several figures.

In the drawings I have shown, for purposes of illustration, a shortwall mining machine of well known construction having a main frame 1 adapted to rest upon and slide over the floor of the mine. Upon the main frame 1 is mounted a motor 2 which is connected by suitable gearing, not shown in the drawings, with the cutter chain 3 and with the feeding devices by which the machine is fed into the coal. As here shown these feeding devices comprise two winding drums 4 and 5, upon which are windable the feed ropes 6 and 7 respectively the free ends of which are adapted to be connected to suitable abutments outside of the machine in such a manner that suitable strains upon the ropes will move and guide the machine over the floor of the mine in the manner well understood in the art.

As these devices are well understood by those skilled in the art, and as they form no part in the present invention, further description is not thought to be required at this time. The cutter chain 3 is of well known construction and is provided with renewable cutter bits 8 adapted to engage the coal to cut it. The cutter chain 3 is adapted to travel in guideways formed on the edges of the cutter arm 9 which projects horizontally from and is rigidly attached to the main frame 1.

Formed in each side of the main frame 1 is a laterally projecting semi-cylindrical extension 10 in which is longitudinally slidable a tubular member 11 having laterally projecting bosses 12 to which are attached the guard angle bars 13. The guard angle bars 13 extend parallel with the chain 3 and have vertically disposed flanges 14 which project upwardly along the chain outside the path of the cutter bits 8, and horizontally disposed flanges 15 which extend inwardly above the cutter chain to guard it against accidental

contact with the person of the operator. At their outer ends the flanges 15 are connected together by the cross bar 16, thus forming a rigid rectangular frame supported by the tubular members 11, and longitudinally slideable with said members into a recess of the main frame.

Slidable in the tubular members 11 are extension tubes 17 which are connected together at their outer ends by a yoke casting 18 to form a rigid frame supported by said tubular members and constituting a telescoping extension thereto. Angle bars 19 attached to and rearwardly projecting from the yoke casting 18 are positioned to lie in the angles of the angle bars 13, and are held in sliding relation therewith by secondary flanges 20 and 21 formed thereon. Lugs 22 and 23 formed on the flanges 13 and 19 serve to limit outward movement of the angle bars 19 relative to the angle bars 13.

Within the tubular members 11 and 17 are compression springs 24 which engage abutments 25 of the main frame and abutments 26 of the yoke casting 18, and the reaction of these springs tends to move said yoke casting to the outer limit of its travel along the cutter bar.

In the operation of a mining machine such as is here illustrated the machine is first positioned at one side of the working place, with the cutter arm projecting towards the coal face. After the cutter chain is set in motion the machine is moved longitudinally forward to thrust the cutter arm endwise into the coal to make the sumping or entering cut. After the machine is fully sumped it is moved laterally to cut a kerf across the coal face, and when this kerf is completed the machine is moved away from the face to withdraw the cutter arm from the coal. As heretofore constructed the unprotected moving cutter chain constitutes a serious menace to the operator and his assistant during the sumping and withdrawal of the machine, thereby materially adding to the risks involved in mining coal. In a machine equipped with my improved chain guard the entire length of the cutter chain is at all times protected. As the cutter bar advances into the coal the yoke casting 18, which may be rounded, as shown, or otherwise suitably shaped to ride easily along a vertical wall, contacts with the coal face and is pushed rearwardly of the cutter arm causing the compression of the springs 24 and sliding the angle bars 13 and 19 into the recess of the main frame. When the machine is withdrawn from the coal the reaction of the springs 24 automatically moves the yoke 18 forward restoring the angle bars 13 and 19 to the chain guarding position, rendering impossible accidental contact with the moving chain and its cutter bits.

It is to be understood that I do not limit

myself to the precise construction here illustrated, as these devices may be subject to wide variation without departure from the spirit of my invention. Furthermore, it will be obvious that while I have shown the invention applied to a particular type of mining machine, namely, the shortwall type, it may be adapted to other types, if desired.

What I claim is:—

1. In a machine of the class described, the combination of a main frame, a cutter extending therefrom, a normally projected cutter guard embracing the sides of said cutters made up of a plurality of telescoping sections, supporting means for said guard to permit said guard sections to be moved rearwardly and uncover the side edges of said cutter upon contact with the coal face as the cutter advances into the coal, and resilient means housed by the guard to automatically return said guard sections to cutter guarding position as the cutter is withdrawn from the coal.

2. In a machine of the class described, the combination of a main frame, a cutter extending therefrom, a normally projected cutter guard section embracing the sides of said cutter and mounted in said main frame to slide longitudinally relative to said cutter, a second cutter guard section embracing the sides of said cutter and mounted to slide longitudinally in said first named guard section, both of said sections adapted to move rearwardly and telescope upon contact with the coal face as the cutter advances into the coal, and means housed by the guard sections to automatically return said guard sections to cutter guarding position as the cutter is withdrawn from the coal.

3. In a device of the class described, the combination in a mining machine, of a main frame, an elongated kerf cutter mounted thereon, and means to actuate said kerf cutter and feed it into the coal to form a kerf therein, angle bars mounted upon said machine adapted to slide longitudinally thereof and normally extending in guarding position along said kerf cutter, inwardly projecting flanges on the arms of said angle bars, auxiliary angle bars telescopically mounted in said first named angle bars on the flanges thereof, and means acting automatically to move said angle bars into guarding position as said cutter withdraws from the coal.

4. In a device of the class described, the combination in a mining machine, of a main frame, an elongated kerf cutter mounted thereon, and means to actuate said kerf cutter and to feed it into the coal to form a kerf therein, guideways carried by said main frame, sleeve members slidably mounted in said guideways, angle bars carried by said sleeve members and normally extending in guarding position along said kerf cutter, and means mounted in said sleeve members acting automatically to move said angle bars

into guarding position as said kerf cutter withdraws from the coal.

5. In a device of the class described, the combination in a mining machine, of a main frame, an elongated kerf cutter mounted thereon, and means to actuate said kerf cutter and to feed it into the coal to form a kerf therein, guideways carried by said main frame, sleeve members slidably mounted in said guideways, angle bars secured to said sleeve members and normally extending in guarding position along said kerf cutter, auxiliary sleeve members mounted in said first named sleeve members, angle bars carried by said auxiliary sleeve members and normally extending in guarding position along said kerf cutter, and means mounted in said sleeve members acting automatically to move said angle bars into guarding position as said kerf cutter withdraws from the coal.

6. In a device of the class described, the combination in a mining machine, of a main frame, an elongated kerf cutter mounted thereon, and means to actuate said kerf cutter and to feed it into the coal to form a kerf therein, guideways carried by said main frame, sleeve members slidably mounted in said guideways, angle bars carried by said sleeve members adapted to slide longitudinally of the machine and normally extending in guarding position along said kerf cutter, inwardly projecting flanges on the arms of said angle bars, auxiliary sleeve members mounted in said first named sleeve members, angle bars carried by said auxiliary sleeve members and telescopically mounted upon said flanges, and means mounted in said sleeve members acting automatically to move said angle bars into guarding position as said kerf cutter withdraws from the coal.

7. In a device of the class described, the combination in a mining machine, of a main frame, an elongated kerf cutter mounted thereon, and means to actuate said kerf cutter and to feed it into the coal to form a kerf therein, semi-cylindrical guideways carried by said main frame, tubular members slidably mounted in said guideways and having laterally extending bosses engaging said guideways, angle bars secured to said bosses and adapted to move longitudinally of the machine to occupy guarding position extending along opposite sides of said kerf cutter and adapted to engage the coal face to be moved thereby rearwardly in said guideways when said kerf cutter is thrust longitudinally in the coal, and means housed in said tubular members and guideways and acting to automatically move said tubular members and angle bars outwardly into guarding position as said kerf cutter is withdrawn from the coal.

8. In a machine of the class described, a main frame, an elongated digging device

mounted thereon, means to actuate said digging device and to feed it into the material, guideways carried by said main frame, a pair of guards slidably mounted in said guideways and movable longitudinally thereof to occupy a guarding position extending along the exposed portions of said digging device, a cross-bar connecting the ends of said guards and adapted to engage the material, said bar having its ends projected laterally beyond said guards, and automatically acting means associated with the projecting ends of said bar to move said guard outwardly along said guideway as the digging device is withdrawn from the material.

9. In a machine of the class described, a main frame, an elongated digging device mounted thereon, means to actuate said digging device and to feed it into the material, guideways carried by said main frame, a pair of guards slidably mounted in said guideways and movable longitudinally thereof to occupy a guarding position extending along the exposed portions of said digging device, a cross-bar connecting the ends of said guards and adapted to engage the material, said bar having its ends projected laterally beyond said guards, guide means secured to the projecting ends of said bar and slidably associated with said main frame, and means associated with said guide means to automatically move said guard outwardly along said guideway as the digging device is withdrawn from the material.

10. In a machine of the class described, a main frame, an elongated digging device mounted thereon, means to actuate said digging device and to feed it into the material, guideways carried by said main frame, a pair of guards slidably mounted in said guideways and movable longitudinally thereof to occupy a guarding position extending along the exposed portions of said digging device, a cross-bar connecting the ends of said guards and adapted to engage the material, said bar having its ends projected laterally beyond said guards, telescopic means secured to the projecting ends of said bar, and means housed by said telescopic means automatically acting to move said guard outwardly along said guideway as said digging device is withdrawn from the material.

In testimony whereof I have hereunto set my hand.

ROBERT R. DUNLOP.
